UNITED STATES PATENT OFFICE.

CHARLES A. CADWELL, OF CLEVELAND, OHIO, ASSIGNOR TO THE ELECTRIC RAILWAY IMPROVEMENT COMPANY, OF CLEVELAND, OHIO, A CORPORATION OF OHIO.

FURNACE.

1,322,756.

Specification of Letters Patent. Patented Nov. 25, 1919.

Application filed April 28, 1915. Serial No. 24,397.

To all whom it may concern:

Be it known that I, CHARLES A. CADWELL, a citizen of the United States, and a resident of Cleveland, county of Cuyahoga, 5 and State of Ohio, have invented a new and useful Improvement in Furnaces, of which the following is a specification, the principle of the invention being herein explained and the best mode in which I have contemplated 10 applying that principle, so as to distinguish it from other inventions.

The present improvements relate in general to furnaces, and more particularly to a melting furnace, such as a furnace for 15 heating crucibles or the like, although the several features of improvement involved are not necessarily limited to use in this connection. The present improvements consist, briefly stated, in the provision of more 20 efficient means for starting such furnaces and in better means for regulating and controlling the induced supply of air for combustion. The improvements include a device for preliminarily heating the vaporizing 25 coil by an auxiliary flame, which is discontinued after the furnace proper has been lighted and has developed the primary source of heating such coil. Different kinds 30 of oil require varying degrees of preheating for the best operation of an oil furnace of 35 the type herein described, in fact, the degree of heating that may cause a furnace to operate successfully with one oil may cause the pipes to clog with a different kind 40 of oil. Accordingly, in the present furnace not only is provision made for varying or 45 regulating the temperature of such preheating coil but the latter is also so connected, that if from the above, or any other cause, 50 it is desired to replace the coil, it may be quickly and easily removed and a new one 55 substituted for it without disturbing the lining of the furnace proper. The present improvements also include means for in- 60 creasing or decreasing the resistance of the furnace chamber to the flow of gases, and thus indirectly decreasing or increasing the amount of air current induced, by varying 65 the total amount of discharge area for exit 70 gases. To the accomplishment of the foregoing and related ends, said invention, then, 75 consists of the means hereinafter fully described and particularly pointed out in the 80 claims.

55 The annexed drawing and the following

description set forth in detail certain mechanism embodying the invention, such disclosed means constituting, however, but one of various mechanical forms in which the principle of the invention may be used.

60

In said annexed drawing:—

Figure 1 is a vertical section through my improved furnace; and Fig. 2 is a plan view of a part.

As shown in Fig. 1, such furnace comprises a furnace chamber 1, proper, which is of general cylindrical form, and is constructed of suitable heat resisting material, such for example, as fire-clay, mounted within a suitably shaped metal casing 2. 65 This cylindrical furnace chamber 1 is adapted to be closed when desired by means of a movable top or cover 3, mounted upon a vertical shaft or pivot 4, by means of which the said top or cover may be swung to one 70 side or the other in order to give access to the interior of the furnace. Said top or cover may also be raised or lowered and the space between said cover and the top 75 of the furnace chamber, through which the 80 gases of combustion tend to flow, be varied to regulate the induction of air through the inlet orifice. To facilitate such raising and lowering, a handled cam 5 is rotatably mounted on shaft 4 so as to coöperate with 85 an opposed cam-collar 5^a fixed on said shaft, as will be readily understood. The cover 3, is provided with a central aperture 6, which in turn is adapted to be covered by means 90 of a second cover 7. At one side, the fur- 95 nace chamber 1, is provided with a hollow lateral extension 8, which in longitudinal cross-section, is of tapered form, being of increasing diameter from its outer end to its inner end, where it opens into the furnace proper. The outer end of the bore in extension 8 is beveled, so as to flare slightly, as shown in Fig. 1.

Within the chamber, upon the bottom of the same, there is preferably provided a seat 100 in the form of a block 9, upon which the crucible or melting pot 10, is preferably placed.

The furnace is also provided with another extension or rather supplemental chamber 105 11, preferably disposed to one side and above the same, and connected by means of a passage 12 with the interior of the fur- 110 nace proper. This chamber 11 consists of a cylindrical casing open at its upper end 13,

and has a lateral opening 14, into which a starting torch 15 is arranged to direct a flame. As best shown in Fig. 2, said casing is preferably split in a central vertical 5 plane, so as to permit the ready removal from within the same of the preheating, or vaporizing coil presently to be described.

Starting torch 15 is connected by means of a conduit 16, to the valve-controlled main 10 fuel-supply conduit 17, a separate valve 18 being provided for closing this connection, except at starting. A continuation 17^a of the fuel-supply conduit 17 extends preferably to the top of the chamber 11, and then 15 passes downwardly through the same in the form of a coil 19. The conduit 17^a after passing out of the chamber 11 near the bottom of the latter, curves downwardly, terminating in a nozzle 20, arranged to inject 20 fuel into the lateral extension 8 of the furnace. The conduit section 17^a, including the coil 19, is rendered separable from the main conduit 17 by interposing a union 17^b at a suitable point in the line, thus making it possible 25 to replace one coil with another by simply breaking the joint at such union and opening the sectional casing of chamber 13.

Various types of fuel may be supplied to the furnace under various conditions, but 30 preferably the fuel which will be supplied, will be oil under pressure, which will cause the same to be injected into the lateral extension 8, from the nozzle 20 when the control valve 21 in the conduit is opened.

35 In operating, the furnace will be started in the following manner by slightly opening valve 18, allowing cold oil to flow through the starting torch 15 in quantity sufficient to fill a small pan 22, which is suspended below 40 the torch burner. Valve 18 is then closed, and the small pan of oil ignited and allowed to burn with a red flame, which heats the burner of the torch. Upon now again opening valve 18, the heated torch will discharge 45 a spray of vaporized oil, which is ignited and the flame thus produced is discharged through the opening 14 against the vaporizing coil 19. The latter is thereby quickly heated and the operator may thereupon open 50 slightly valve 21, admitting a small quantity of oil to said coil. A spray of vaporized oil is thus immediately obtained at nozzle 20, which may be ignited by the operator, and combustion so obtained both in the furnace proper and in the auxiliary chamber 13.

The main furnace, having cold walls on the start, will not immediately properly consume the normal amount of fuel and the operator will accordingly at first open the control valve 17 but slightly, and regulate the induction of air at the inlet orifice of lateral extension 8 by lowering the top, or cover 3, until it rests directly upon the walls of the furnace and also by closing cover 7, as shown 65 in Fig. 1, so that all of the gases of com-

bustion must obtain exit by flowing through duct 12 and chamber 13. After a few minutes, the flow of hot gases above mentioned through duct 12 is sufficient alone, to heat the vaporizing coil 19, and the auxiliary 70 torch 15 is stopped by closing valve 18. As the furnace walls become heated, the amount of fuel supplied is increased by further opening valve 21 and the amount of air induced is increased by opening cover 7 over the discharge orifice 6, the amount of air thus induced being increased by making the opening in the outer end of the lateral extension 8, funnel-shaped, as previously described. 80

For the highest heat, the maximum quantity of oil and air are supplied, the first by further opening cover 7 and the second by raising the top or cover 3 of the furnace and thereby increasing the total area of discharge area for exit gases. 85

By means of the foregoing starting mechanism, the fuel for combustion in the furnace may be preheated rapidly without the necessity of supplying a fire in the interior of the furnace proper. At the same time, when, and as soon as, the temperature in the auxiliary chamber 19 has been brought to the proper degree for vaporizing the oil in the supply conduit section 17^a a further rise 90 in such temperature is prevented by the simple expedient of raising one or both of the covers 3 and 7. Thus the tendency of the fuel to break down and clog up the coils under extreme heat is entirely avoided and yet thorough vaporization secured. When it does become necessary to replace the coil, this is very easily accomplished, as has already been explained, by reason of the disposition and construction of parts. 95 100 105

Other modes of applying the principle of my invention may be employed instead of the one explained, change being made as regards the mechanism herein disclosed, provided the means stated by any of the following claims or the equivalent of such stated means be employed. 110

I therefore particularly point out and distinctly claim as my invention:—

1. In a furnace, the combination of a furnace chamber proper having an opening therein; a nozzle arranged to inject fuel into such opening; a hollow extension to said furnace chamber; a fuel-supply conduit leading to said nozzle and having a coil disposed in such extension; and a starting torch arranged to direct a flame into such extension. 115 120

2. In a furnace, the combination of a furnace chamber proper having a lateral opening therein; a nozzle arranged to inject fuel into such opening; a hollow extension to said furnace chambers; a fuel supply conduit leading to said nozzle and having a coil disposed in such extension; and a start- 125 130

ing torch connected to said conduit and arranged to direct a flame into such extension.

3. In a furnace, the combination of a furnace chamber proper having a lateral opening therein; a nozzle arranged to inject fuel into such opening; a hollow extension to said furnace chamber connected with the interior thereof; a fuel supply conduit leading to said nozzle and having a coil disposed in such extension, the section of said conduit including such coil being separable from the remainder of said conduit and removable from said extension; and a starting torch arranged to direct a flame into such extension.

4. In a furnace, the combination of a furnace chamber proper having a lateral opening therein; a nozzle arranged to inject fuel into such opening; a hollow extension to said furnace member connected to the interior thereof; a fuel supply conduit leading to said nozzle and having a coil disposed in such extension, a starting torch connected to said conduit and arranged to direct a flame into such extension; and a valve controlling the connection of said torch with said conduit.

5. In a furnace, the combination of a furnace chamber proper having a lateral opening therein; a nozzle arranged to inject fuel in such opening; a hollow extension to said chamber comprising a sectional casing connected with the upper portion of said chamber's interior; means for holding said sectional casing together; and a fuel supply conduit leading to said nozzle and having a coil disposed in such casing, the section of said conduit including such coil being separable from the remainder of said conduit and removable from said casing with the outer section of the same upon the removal of said holding means.

6. In a furnace, the combination of a furnace chamber proper having a lateral opening therein; a nozzle arranged to inject fuel in such opening; a hollow extension to said chamber, comprising a sectional casing connected with the upper portion of said chamber's interior; and a fuel supply conduit leading to said nozzle and having a coil disposed in such casing, the section of such conduit including such coil being separable from the remainder of said conduit and removable from said casing upon separating the sections thereof; and a starting torch

connected to said conduit and adapted to direct a flame into such extension.

7. In a furnace, the combination of a furnace chamber proper having an opening therein; a nozzle arranged to inject fuel into such opening; a hollow extension to said furnace chamber; a fuel-supply conduit leading to said nozzle and having a coil disposed in such extension; a vertically movable cover for said furnace; and means for thus moving the same, whereby the draft through the latter may be increased and the flow of heated gases through such extension simultaneously decreased.

8. In a furnace, the combination of a furnace chamber proper having an opening therein; a nozzle arranged to inject fuel into such opening; a hollow extension to said furnace chamber; a fuel supply conduit leading to said nozzle and having a coil disposed in such extension; a vertically movable cover for said furnace; means for thus moving and maintaining said cover in the desired vertical position, whereby the draft through said furnace may be increased and the flow of heated gases through such extension simultaneously decreased.

9. In a furnace, the combination of a furnace chamber proper having a lateral opening therein; a nozzle arranged to inject fuel in such opening; a hollow extension to said chamber; a fuel supply conduit leading to said nozzle and having a coil disposed in such extension; a movable cover for said furnace; means for adjusting and maintaining the position of said cover including a handled cam and connections between the same and said cover.

10. In a furnace, the combination of a furnace chamber proper having a lateral opening therein; a nozzle arranged to inject fuel into such opening; a split hollow extension to said furnace chamber; a fuel supply conduit leading to said nozzle and having a coil disposed in such extension; said conduit containing said coil being removable when said extension is split apart; and means for controlling the flow of heated gases through such extension.

Signed by me, this 23 day of April, 1915.

CHARLES A. CADWELL.
